UNITED STATES PATENT OFFICE

2,685,267

THREAD CLAMPING MECHANISM FOR
BUTTON SEWING MACHINES

William T. Maxant, Ayer, Mass.

Original application May 3, 1945, Serial No.
591,656. Divided and this application March
22, 1951, Serial No. 216,976

5 Claims. (Cl. 112—253)

1

This application is a division of my prior application, filed May 3, 1945, Ser. No. 591,656, now Patent No. 2,563,854, granted August 14, 1951, for Stop Motion Mechanism for Button Sewing Machines.

This invention relates to improvements in button sewing machines, particularly of the character used for sewing flat buttons on work of various kinds, such as strips of cloth, articles of clothing, and the like. It relates more particularly to machines which are used for attaching either two-hole or four-hole buttons thereto by stitching through the eyes of the buttons and the cloth, especially such machines as are operated by power.

One object of this invention is to provide for the locking of the thread at the completion of the stitching cycle, and automatically to provide for breaking of the thread and ready separation of the work therefrom.

A still further object of the invention is to improve the construction of the thread lock, the mounting thereof on the face plate instead of the top of the arm; and the actuation of the thread lock or clamp from the power cam of the machine through linkage connections that extend along the under side of the base, up the standard and through the arm to the clamp mounted on the face plate.

These objects may be accomplished according to one embodiment of the invention by mounting a thread lock or clamp on the head of the machine and through which the thread passes to the needle. A means is provided in the thread lock or clamp for adjusting the action thereof in its released and engaged positions. This thread clamp preferably is actuated by means which functions in timed sequence with the stitching cycle so as to clamp the thread at the completion of the stitching cycle and cause breaking thereof automatically upon movement of the button clamp.

This embodiment is illustrated in the accompanying drawings in which:

Fig. 1 is a side elevation of the button sewing machine showing the thread lock or clamp applied thereto;

Fig. 2 is a partial front elevation thereof;

Fig. 3 is a horizontal section through the thread clamp on the line 3—3 in Fig. 2;

Fig. 4 is a cross section through the machine and lower portion of the standard;

Fig. 5 is a similar view toward the front of the base; and

Fig. 6 is a partial bottom plan view of the base

2 showing the operating mechanism in elevation and with a part in section, taken on the line 6—6 in Fig. 5.

The machine is adapted for end operation with the operator facing the machine, and with the machine supported on a table, work-bench, or other support, generally designated at S. Accordingly, the machine is constructed with a machine bed designated generally by the numeral 1, adapted to be mounted on or secured to the support S.

A hollow base 2 is connected with the bed 1, by pivotal connections 3 for swinging movement of the base 2, away from the bed 1 to gain access to the operating parts of the machine housed within the base. Normally the base is held in a closed position on the machine bed 1 by a thumb screw 4, which extends through an orifice in one side of the base 2 and engages a recess in a lug attached to the bed 1, which lug extends upwardly within the base.

The base frame 2 encloses the principal operating parts of the machine and confines these from entanglement of the cloth therewith, as well as presenting a more attractive appearance to the machine. The base 2 has a forward extension 6 on the front end thereof over which the buttons clamp is disposed as hereinafter described, which extension is of appreciably less width than the base, to facilitate the manipulation of the articles and access to the button clamp by the operator.

The base 2 also supports the usual upstanding standard 7 fixed on the base, with an arm 8 extending horizontally from the upper end of the standard 7, which arm carries the usual sewing head 9 at the free end thereof. These parts are hollow and communicate at their lower end with the base 2. These parts comprising the standard 7, arm 8, and sewing head 9 are preferably cast integral and either secured rigidly on the base 2 or cast integral therewith. The outer side of the sewing head 9 is initially open but is enclosed by a cover plate 10 which is detachably mounted thereon in the usual manner.

The sewing head 9 has the usual needle bar 11 mounted therein and guided at the top through a bushing 12 for reciprocating movement vertically through the head 9. The lower end of the needle bar 11 carries the usual sewing needle 13. The needle bar 11 is adapted to be reciprocated sufficiently far to project the needle 13 into the base extension 6 for cooperating action with sewing instrumentalities contained therein.

For the purpose of reciprocating the needle bar

11 axially, this needle bar is connected with one end of a rocker arm that extends lengthwise through the hollow arm 8 and has an operative connection with the upper end of a pitman 17. The pitman 17 extends vertically through the standard 7 as shown in Fig. 4, and downward into the base 2, and is adapted to be reciprocated vertically to cause reciprocating movement of the needle bar 11 in the head 9.

The lower end of the pitman 17 is in the form of an eccentric strap 18 which surrounds an eccentric 19 fixed on a main drive shaft 20 that extends lengthwise through the base 2. The drive shaft 20 is journaled in bearings at opposite ends of the base 2 and in a bearing 23 in a transverse partition 23' intermediate the ends of the base. The drive shaft is connected with the operating parts of the machine and drive said parts.

At the other end of the machine the drive shaft 20 carries stitch-forming mechanism, preferably including a rotary looper 26 on a holder 24 on the shaft 20, in cooperating relation with a thread deflector 27, which elements will cooperate with the needle 13 to accomplish the desired stitching action in the manner well-known in the art.

At the opposite end, the drive shaft 20 projects through a bushing externally of the base 2, and has mounted on said projecting end of the shaft fixed and free pulleys 33 and 34, respectively, the former being fixed to the shaft 20 and adapted to receive a drive belt from a suitable source of power. On the extreme end of the shaft 20 is mounted a hand wheel 35 pinned to the shaft for manual turning thereof when desired.

The machine is provided with a shifter yoke, 36, and generally designated by the numeral 35, and formed by a pair of shifter arms which embrace opposite sides of the belt and shift the belt from one pulley to the other, either to drive the shaft 20 when the belt engages the pulley 33 or to run free of the shaft on the loose pulley 34. The shifter yoke 36 is connected with a brake shoe 37 which moves with the yoke and carries a lining 38 fixed to the brake shoe 37 to move the lining into frictional engagement with the pulley 33, so as to stop the rotation of the pulley and drive shaft 20 when the brake lining 38 is shifted into engagement therewith. The parts are so disposed that the lining will be shifted into engagement with the pulley 33 when the belt is shifted from this pulley onto the pulley 34 by axial displacement of the yoke 36.

The brake shoe 37 extends transversely of the base 2 and is guided at one end on a pin guided in the base 2. The opposite end of the shoe 37 is formed integral with the support which carries the arms forming the shifter yoke 36. This support is mounted rigidly on a stop shaft 40 extending in the base 2.

The stop shaft 40 extends lengthwise into the base 2 and is guided in bearing 42 therein for axial movement under the influence of a helical spring 43, which is sleeved over the stop shaft 40, and bears at one end against the partition 23' extending transversely in the base 2 and carrying the bearings 23 and 42. The opposite end of the spring 43 bears against a stop bumper 45 pinned to the stop shaft 40. The spring 43 normally tends to move the stop shaft 40 axially rearwardly, unless the shaft is anchored in its operating position as shown. When moved to its released position, the shaft 40 will be moved upward and carry with it the stop bumper 45 and also move the shifter yoke 36 to cause the driving belt to engage the free pulley 34, which will

also stop the operation of the machine by the engagement of the brake lining 38 with the pulley 33. For a more detailed explanation of the stop motion mechanism, reference is made to the aforesaid Patent No. 2,563,854, wherein the same is described more fully.

The stop bumper 45 also carries a coiled spring 46 (Fig. 4) mounted in the end thereof, but projecting slightly therefrom in position to engage a stop finger 47 fixed to the drive shaft 20. The stop finger 47 is in such position that its transverse vertical plane of operation will cause it to engage the stop bumper 45 when the latter is moved to its stop position at the completion of a sewing cycle, thus locking the further rotation of the drive shaft 20 until the machine is re-set.

The stop shaft 40 is adapted to be shifted axially to its locked position by means of a hand lever 48 pivotally mounted at 49 in the base 2, so that the upper end of the lever 48 projects above the base in position for convenient reach by the operator for manipulation at the starting of a new sewing cycle. The lower end portion of the lever 48 is bifurcated and engages a pin 50 which projects laterally from the back face of the stop bumper 45. Thus upon shifting the hand lever 48, the stop shaft 40 would be moved to its retracted position, against the tension of the spring 43, and would be locked in said operating position for another sewing cycle.

Provision is made for locking the stop shaft 40 in its retracted or set position. This stop shaft 40 is accordingly provided with a block 57, fixed thereon and extending downwardly from the stop shaft in position to be engaged by a stop latch 58 that has a shoulder to engage under the block 57 and hold the latter and the stop shaft 40 in retracted positions. The latch 58 has an extended end portion that engages the lower face of the block 57 when the machine is in its blocked or inoperative position, so that the latch 58 will be ready to engage the block 57 again upon movement of the latter beyond the shoulder.

The latch is normally drawn upward by a coiled spring 61 connected therewith.

The latch 58 is pivotally supported on a bracket or casting 63 which is mounted in the base 2. Said latch 58 underlies a transverse arm 64 integral with the bracket 63 and extending transversely therefrom.

The latch 58 is adapted to be released by a tripper member 65 pivotally mounted at 66 on the transverse arm 64 in a position with one end thereof overlying the latch 58. The opposite end of the tripper member 65 carries a tripper finger 67, which is slotted and adjustable lengthwise relative to the tripper member 65 by an adjusting screw 68 for providing properly timed operation of the machine.

The finger 67 has a down-turned end 69 in position to be engaged by a stud 70 mounted on the upper face of the upper cam 71. The stud 70 is provided with an inclined face to ride under the down-turned end 69 of the tripper finger 67 to cause an upward swinging movement of said finger when engaged by the stud which will force the opposite end of the tripper 65 downwardly and cause the latch 58 to be depressed out of latching engagement with the block 57. This will release the stop mechanism and move it forward to its blocking position.

The cams are shown at 71 and 72. These cams are mounted on a stub shaft 73 integral with a worm gear 74 in mesh with a worm 75 fixed to

the main drive shaft 20. The stub shaft 73 is journaled on a pin fixed in the base 2 and extending downwardly therein, and is retained in place by means of a screw 76 (Fig. 6) fixed in the end of the journal pin and retaining the stub shaft thereon.

The button clamp is illustrated generally by the numeral 89 and is provided with a pair of clamping jaws 90 between which the button is inserted. The button clamp holds the button in place over the cloth, which latter may be positioned on the cloth plate or underjaw 92.

Provision may be made for actuating the button clamp in properly timed relation and for raising and lowering said clamp, which features are not illustrated or described in detail, but reference may be had to the aforesaid application for a more detailed description thereof.

The usual thread tension devices may be used as indicated generally at 145 and 146, which tension devices may be of any well-known construction and need not be described in detail.

The thread is supplied from a spool mounted on a stand generally designated at 147 at the back end of the machine, as shown in Fig. 1. This stand includes a supporting plate 148 and integrally cast flaring sides 149 formed in one integral piece with said plate, so as to extend over the top and down opposite sides of the pulleys 33 and 34. Thus the thread holder also forms a guard for the pulleys and belt as well as to support the thread.

The thread holder 147 is supported by brackets 150 secured upon the base 2. An upstanding hook member 151 is carried by the stand 147 and has an eyelet in the upper end thereof in position to overlie the spool mounted on the stand for guiding the thread therefrom.

The face plate 10 has the usual eyelets 152 and 153 (Fig. 2) in the upper and lower portions thereof, and an intermediate thread guide generally indicated at 154. A thread guide is shown also at 155 projecting through a slot in the face plate 10 and carried by the needle bar 11.

Mounted on the face plate 10 is a thread clamp, generally designated at 156, through which the thread extends from the eyelet 152 before passing through the thread guide 154 to the needle 13.

The thread clamp 156 is shown more in detail in Fig. 3, and includes a bushing 157 having an end face portion secured to a stop plate 158 by set screws 159 which pass through the stop plate 158 and through the flanged portions of the bushing 157 and are threaded into the face plate 10 for securing these parts rigidly to the face plate. The bushing 157 has a vertical slot 160 therethrough for receiving and guiding the thread through the clamp to a position behind the stop plate for clamping action thereagainst.

Slidably mounted in the bushing 157 is a clamping stud 161 having an end face normally spaced from the clamp stop plate 158 but in position to cooperate therewith for clamping the thread therebetween. The thread guide slot 160 is intermediate the opposite sides of the stud 161, so as to locate the thread in clamping position. The stud is pressed normally backward away from clamping position by a coiled spring 162 sleeved thereover and interposed between the end of the bushing 157 and a collar 163 clamped on the bushing. A pin 164 is telescoped into the end of the clamping stud 161 and guided in the collar 163 for moving the clamping stud to a clamped position, acting as a plunger therefor. A small coiled spring 165 is interposed between

the inner end of the plunger 164 and the bottom of the recess in the clamping stud 161 to cushion the action of the plunger thereon. A hand button 166 is attached to the opposite end of the clamping stud 161 for hand release action thereof if required.

Provision is made for actuating the thread clamp 156 automatically in timed relation with the operation of the machine, so that the thread 10 will be clamped immediately upon the completion of the sewing cycle. I have provided, accordingly, a thread clamp push-rod 167 (Fig. 1) slidably mounted in a guide 168 in the head arm 8, and extending lengthwise of said arm. The push-rod 167 extends through the arm 8. The forward end of the push-rod 167 has an upturned abutment portion 169 in position to engage the plunger 164 on the thread clamping stud 161, so as to push the forward end of the stud into clamping relation with the clamp stop plate 158 and hold the thread therebetween.

The back end of the push-rod 167 is pivotally connected with one arm of a bell-crank lever 170 pivotally mounted at 171 at the upper end 25 of the head standard 7. The other arm of the bell-crank lever 170 is pivotally connected with the upper end of a connecting link 172 that extends downwardly through a slot in a guide plate 173 (Fig. 4), mounted at the under side of the base 2.

The lower end of the connecting link 172 carries a laterally projecting pin 174 disposed in position to overlie an end of a thread-lock finger 175. This thread-lock finger 175 is pivotally mounted intermediate its ends on a support 176 carried by the base partition 23'. The opposite end of the finger 175 is beveled at its upper side and in position to be engaged by a stud 177 secured to a side of the stub shaft 73, as shown 40 in Fig. 5.

Thus, upon the completion of a revolution of the gear 74, and with it the cams 71 and 72, the stud 177 will engage the beveled end of the lock finger 175 and depress said beveled end. This 45 action will push upward on the opposite end of the lock finger, and thereby move upward the link 172, swinging the bell-crank lever 170 to impart forward pushing action to the push-rod 167. This will cause a pushing action to be imparted by the offset end 169 against the plunger 164, thereby pressing the stud 161 forwardly against the tension of the spring 165 to clamp the thread between the end of the stud 161 and the clamp stop plate 158 (Fig. 3). This will 55 cause the thread to be clamped at the completion of the stitching operation, and then upon lifting the button clamp the thread will be broken below the clamp.

The location of the thread lock on the face plate, instead of on top of the arm, as in previous machines, provides for a shorter length of thread to stretch when the lifting of the clamp breaks the thread under the button. This results in a quicker break in the thread, which is a decided improvement.

Before starting the sewing operation, the material is placed beneath the button clamp upon the cloth plate 92 of the button clamp. This should be done when the button clamp is in its elevated position, which will afford ready access thereto for this purpose. The button is then inserted into the clamping jaws 90, and the button clamp 89 is lowered to the position shown in Fig. 1.

The operator then swings the hand lever 48,

which controls the stop motion mechanism. This action frees the shaft 20 for rotation.

The forward movement of the stop shaft 40 by the lever 40 slides the belt shifter 36 inwardly which not only shifts the belt from the pulley 34 to the pulley 33, but also releases the brake lining 38 from the face of the pulley 33 which frees this pulley and the shaft connected therewith for rotation by the belt. The drive shaft 20 is then operated by the pulley 33.

The rotation of the drive shaft 20 reciprocates the needle bar 11 through a stroke sufficient to direct the needle downwardly into the base extension 6 for cooperating stitching action with the looper 26 that is rotated by the main shaft 20 on which it is mounted.

As the revolution of the cam shaft 73 is completed, the stud 177 will engage the beveled end of the lever 175, which will lift the opposite end of the lever and push upward on the link 172 and forwardly on the push rod 167 (Fig. 1) to actuate the clamping stud 161 and clamp the thread against movement.

Then upon lifting of the button clamp 89 the thread will be broken therebelow. The work may then be removed or shifted to another position ready for the sewing of another button.

The particular stitching operation need not be described more in detail, but reference may be had to the aforesaid application for this and any other details of the construction and operation of the machine.

While the invention has been illustrated and described in one embodiment, it is recognized that variations and changes may be made therein without departing from the invention as set forth in the claims.

I claim:

1. A thread lock for a sewing machine comprising a locking plate, a locking member slidably mounted for coaction with the plate to clamp a thread therebetween, a pin slidably telescoped with the locking member for actuating said member, and a spring interposed between and bearing at opposite ends respectively against said pin and locking member, said spring being urged by movement of the pin to apply yieldable locking pressure to the locking member toward the locking plate.

2. A thread clamp for a sewing machine comprising a clamping plate, a clamping member slidably mounted for movement toward and from the clamping plate adapted to receive a thread therebetween, said clamping member having a shank portion fixed thereto for movement with the clamping member, a pin telescoped in said shank portion, and a coiled spring interposed between the pin and the clamping member and transmitting movement from the pin to said member.

3. A thread clamp for a sewing machine comprising a clamping plate, guide means, a clamping member slidably mounted in the guide means for movement toward and from the clamping plate adapted to receive a thread therebetween, said clamping member having a shank portion fixed thereto for movement with the clamping member, a spring connected with the shank portion acting to move the clamping member in one direction, a pin telescoped in said shank portion, and a coiled spring interposed between the pin and the clamping member and transmitting movement from the pin to said member.

4. A thread clamp for a sewing machine comprising a fixed clamping plate, a bushing connected with the clamping plate, an elongated movable clamping member slidably mounted in the bushing with one end projecting therefrom, the opposite end of the clamping member having a clamping face opposed to the clamping plate adapted to receive a thread therebetween, a coiled spring surrounding the projecting end of the clamping member and acting thereon tending to move said member in one direction, a pin telescoped in said end of the clamping member and slidably relative thereto, and a spring sleeved in said end portion of the clamping member and interposed between said pin and the clamping member.

5. A thread clamp for a sewing machine comprising a fixed clamping plate, a bushing connected with the clamping plate, an elongated movable clamping member slidably mounted in the bushing with one end projecting therefrom, the opposite end of the clamping member having a clamping face opposed to the clamping plate adapted to receive a thread therebetween, a coiled spring surrounding the projecting end of the clamping member and acting thereon tending to move said member in one direction, a pin telescoped in said end of the clamping member and slidably relative thereto, and a spring sleeved in said end portion of the clamping member and interposed between said pin and the clamping member and acting in the opposite direction from the first mentioned spring, and a hand button attached to the opposite end of the clamping member and extending externally of the clamping plate for hand release action of the clamping member on the thread.
